COLLAPSIBLE FILING DRAWER

Harry L. Fellowes, Chicago, Ill., assignor to
 Bankers Box Company, Chicago, Ill., a corporation of Illinois

Application November 18, 1938, Serial No. 241,156

8 Claims. (Cl. 229—48)

My invention relates to a collapsible filing drawer of composite construction, i. e., paper board and metal, a drawer which is especially adapted for, but not limited to, use in a collapsible filing cabinet of the kind disclosed and claimed in my United States Letters Patent No. 2,121,190, dated June 21, 1938.

A general object of my invention is to provide such a drawer which readily and easily may be converted from its collapsed or knocked down condition to its erected or useable condition.

Another object of my invention is to provide such a drawer which has paper board side and end walls detachably but rigidly connected by quickly and easily insertible corner posts which are disposed interiorly of the angles between side and end walls of the drawer to interlock in novel and effective manner with cooperating lips carried by metallic bindings for the vertical margins of the connected walls.

Another object of my invention is to provide such a drawer which is characterized in that certain of its walls, preferably all of its side and end walls, are formed of paper board and have their upper and vertical edges embraced and reinforced by a novel metallic binding element, which is so constructed that it quickly and easily may be applied to the edges of the paper board side and end walls of the drawer without perforating or otherwise weakening the paper board in the regions where it is engaged and squeezed by the gripping elements of the metallic binding.

A further object of my invention is to provide a very strong, attractive and generally improved collapsible filing drawer formed from a single piece of paper board having side and end wall sections which are metal reinforced and connected by novel and easily applied wall edge binding elements cooperating with novel and easily applied locking posts disposed interiorly of the angles between vertical margins of contiguous side and end walls of the drawer.

These and other objects, features, and advantages of the collapsible filing drawer of the present invention will hereinafter appear from the following detailed description, wherein reference is made to the accompanying three sheets of drawings, in which

Fig. 1 is a perspective view of a file drawer embodying the improvements of the present invention;

Fig. 2 is a greatly enlarged fragmentary view, in isometric perspective, representative of any one of the corners of any of the wall edge binders;

Fig. 3 is a plan view of a paper board blank used in the construction of the file drawer;

Fig. 4 is a plan view illustrating the drawer as it appears when fabricated to the knocked down or partly completed condition in which it is or may be customarily sold and shipped;

Fig. 5 is an enlarged fragmentary sectional view illustrating one of the wall edge binders as it appears while being applied to an edge of a paper board drawer wall;

Fig. 6 is a view similar to Fig. 5, but illustrating the binder after it has been applied to the drawer wall edge;

Fig. 7 is an enlarged fragmentary horizontal sectional view which may be regarded as taken in the plane of the line 7—7 of Fig. 1 and looking in the direction indicated by the arrows; and

Fig. 8 is a perspective view of one of the corner posts wherewith the end and side walls of my improved file drawer are held in properly erected relationship.

Similar characters of reference refer to similar parts throughout the several views.

The drawer of the present invention preferably comprises a single initially flat sheet 10 of paper board (see Fig. 3) scored and cut to provide a rectangular bottom section 11, side wall sections 12, and end wall sections 13 and 14; each of said end wall sections having a pair of flaps which are appropriately indicated at 13—a and 14—a. 30

The section 13, which is to form the outer ply of a two ply rear end wall, is provided with a horizontal slot 15 arranged to register with notches 16 of the flaps 13—a when the latter are folded against end wall section 13, as shown in Figs. 4 and 7. The purpose of slot 15 and notches 16 is to afford a convenient handhold which may be grasped when the drawer, being removed from the customary filing cabinet case, (not shown) is being carried from place to place. A gummed paper or cloth strip 17 is preferably adhesively applied to bottom section 11 and the contiguous margins of flaps 13—a as shown in Fig. 4.

The section 14, which is to form the outer ply of a two ply front end wall, has its flaps 14—a held in proper position to constitute the inner ply of said front end wall by a fiber strap 18 which receives the inner ends of bolts 19, which in turn cooperate with thumb nuts 20 properly to secure a conventional handle 21 on the outer surface of end section 13 (see Fig. 1).

The construction of those parts of the drawer which I have thus far described may be varied within wide limits. I shall now describe those

features of the drawer with which the present invention is particularly concerned.

Each of the paper board side walls and end walls of the drawer has three of its edges (i. e., the edges which become the upper and vertical edges of the wall in the erected drawer) provided with a binding 22 in the form of an integral strip of metal which will retain the cross sectional shape depicted in Fig. 6 when pressed or otherwise forced to such shape from the cross sectional shape depicted in Fig. 5.

Binding strip 22, being somewhat U-shaped or channel shaped in cross section, comprises the side wall portions 23 and 24 connected by the web portion 25. The free edge of the wall portion 23 is provided with a lip or flange 26 which constitutes one of the cooperating gripping elements of the binding. The others of such gripping elements are the spaced apart parallel beads 27 and 28, and the concavo-convex portion 29 of wall 24. Such concavo-convex portion lies between the beads 27 and 28 and presents its concave face toward the lip or flange 26 of the other wall 23.

The free edge of binding strip wall 24 is in the form of an offset lip 30 connected with bead 28 by a shoulder 31. In the erected drawer the portions of the lip 30 and shoulder 31 which appear on the horizontal reaches of the binding strips are superfluous, but those portions of such lip and shoulder which appear on the vertical reaches of the strips are very important, because they cooperate with the vertical locking corner posts presently to be described.

Before the application of any of the binding strips 22 to the edges of its appropriate drawer wall, its side walls 23 and 24 are suitably notched so that they may appear to be mitered, as at 32, where the binding passes around an upper corner 40 of the drawer wall (see Fig. 2). Moreover, the horizontally extending portions of the lips 30 and shoulders 31 are cut away for a short distance from each corner, as most clearly illustrated at 33 in Fig. 2, to permit the application and removal 45 of the locking corner posts presents to be described.

The locking strips 22 appear as shown in Fig. 5 while being applied to their appropriate drawer wall edges. When their application has been completed they appear as shown in Fig. 6.

It will be noted that the paper board wall portion which is embraced by each binding strip 22 has one of its faces (the inner face) indented along two parallel lines by the beads 27 and 28, and has its other (outer) face indented by lip 26 of binder wall portion 23 to cause a shift (by deformation but not perforation) of paper board material into the concave face of the concavo-convex portion 29 of binder wall 24. Thus each binding strip tightly and permanently engages its embraced paper board drawer wall without perforating or appreciably weakening the latter.

The binding strips 22 which are applied to the two ply end walls of the drawer have somewhat wider web portions than do the binding strips which are applied to the one ply side walls of the drawer.

I shall now describe the vertical locking posts, shown at 34, of which each drawer comprises four (see Figs. 1, 7, and 8).

Each of the posts 34 is formed from relatively stiff sheet metal and is generally L-shaped in cross section, one of the sides 35 of the L being wider than the other side 36, but each side being provided with a shoulder 37 and a hook flange 38,

having its free edge lying closely adjacent to but spaced from shoulder 37. The hook flange 38 in each instance is adapted more or less snugly and slidably to receive a binding strip flange 30 and the space between each shoulder 37 and the free edge of its associated hook flange 38 is just sufficient to pass a binding strip shoulder 31.

The drawer is or may be shipped to the customer in the form shown in Fig. 4 (with the handle 21 either attached or unattached) and accompanied by four of the locking corner posts 34.

When the drawer is to be erected for use in a filing cabinet its side and end walls are moved to the positions depicted in Fig. 1 and one of the corner posts 34 is vertically positioned interiorly 15 of each of the angles formed by the side and end walls of the drawer—in locking engagement with the vertical reaches of the edge bindings of the walls which form such angles.

In applying each corner post 34 it is extended 20 through a space 33 at a corner of one of the end wall bindings. The hook flange 38 of its narrower side 36 is then engaged around the upper end of the vertical reach of the proximate flange 30 of such end wall binding. The post is then forced 25 downwardly until the hook flange 38 of its wider side 35 passes through the space 33 of the adjacent side wall binding to engage around the vertical reach of the proximate flange 30 of such side wall binding. The post is then pressed downwardly (as by forcing a thumb against a coin lying against the upper end of the post) to the position depicted in Fig. 1.

With each post thus properly positioned and 35 cooperating with the metallic bindings of its associated side and end walls, the latter are held effectively but detachably in proper erected relation to each other by strong and rigid corner structures which serve to prevent any objectionable or observable relative movements between 40 the proximate edges of the end and side walls connected by such corner posts.

Having thus illustrated and described a preferred embodiment of my invention, what I claim 45 as new and desire to secure by Letters Patent of the United States is:

1. A collapsible filing drawer or like collapsible receptacle comprising a bottom section and side wall and end wall sections of non-metallic material hingedly connected with appropriate edges of the bottom section, such wall sections being adapted to be moved to vertical positions wherein they define four vertical receptacle corners each defined by a vertical edge of one wall section being presented to the inner face of a contiguous wall section at a vertical edge of the latter, a metallic binding of generally U-shaped cross section embracing and secured upon each vertical edge of each wall section, the inner side 55 wall of each such metallic binding being provided with an offset lip remote from and extending away from the vertical corner with which such binding is associated, and a locking corner post of metal disposed vertically and interiorly 60 of each of such vertical corners, each of such corner posts being generally L-shaped in cross section and having each of its sides turned upon itself to provide a hook flange adapted slidably to engage one of the aforesaid binding lips. 65

2. A collapsible filing drawer or like collapsible receptacle comprising a bottom section and side wall and end wall sections of non-metallic material hingedly connected with appropriate edges of the bottom section, such wall sections 70

being adapted to be moved to vertical positions wherein they define four vertical receptacle corners each defined by a vertical edge of one wall section being presented to the inner face of a contiguous wall section at a vertical edge of the latter, a metallic binding of generally U-shaped cross section embracing and secured upon each vertical edge of each wall section, the inner side wall of each such metallic binding being provided 10 with an offset lip and a shoulder which is substantially normal to such lip and which connects the lip with the binding side wall of which it forms a part, each such lip extending away from one of said vertical corners, and a locking corner post of metal disposed vertically and interiorly of each of such vertical corners, each of said corner posts being generally L-shaped in cross section and having each of its sides conformed to provide both a hook flange adapted slidably to 15 embrace an adjacent metallic binding lip and a shoulder adapted to abut the binding shoulder associated with such lip.

3. In a collapsible filing drawer or the like a vertical corner formed by one vertical edge of 25 one non-metallic wall section being presented to the inner surface of another non-metallic wall section adjacent a vertical edge of the latter, a metallic binder of generally U-shaped cross section embracing and secured upon each of such 30 vertical edges, the inner side wall of each U-shaped binder being provided with an offset lip positioned remote from the corner and which extends away from the said corner, and a locking post of metal disposed vertically and interiorly 35 of such corner, such post being of generally L-shaped cross section and having each of its sides turned upon itself to define a hook flange adapted slidably to engage one of said binding lips, one of said hook flanges being offset laterally to provide a shoulder, whereby one of said offset lips is wedged between the hook flange and said shoulder to assist in preventing either inward or outward movement of said walls relative to each other.

45. 4. In a collapsible filing drawer or the like a vertical corner formed by one vertical edge of one non-metallic wall section being presented to the inner surface of another non-metallic wall section adjacent a vertical edge of the latter, a metallic binder of generally U-shaped cross section embracing and secured upon each of such vertical edges, the inner side wall of each U-shaped binder being provided with an offset lip which extends away from the said corner, the binder of the wall section which presents its inner face to the edge of the other wall section being provided with an abutment shoulder adjacent its offset lip, and a locking post of metal disposed vertically and interiorly of such corner, such post being of generally L-shaped cross section and having each of its sides turned upon itself to provide a hook flange adapted slidably to engage one of said binding lips, one of the sides of the post also being conformed to provide an abutment shoulder adapted slidably to engage the first mentioned abutment shoulder.

5. In a collapsible drawer or the like a vertical corner formed by one vertical edge of one wall section being presented to the inner surface of another wall section adjacent a vertical edge of the latter, each such wall section being

provided with a metallic lip which is spaced from and extends away from such vertical corner in a plane substantially parallel with the wall section by which it is carried, the wall section which presents its inner face to the vertical edge of the other being also provided adjacent its lip with an abutment shoulder, and a locking post of metal disposed vertically and interiorly of such corner, such post being of generally L-shaped cross section and having each of its sides conformed to 10 define a hook flange adapted slidably to engage one of said lips, one of the sides of the post also presenting an abutment shoulder adapted slidably to engage the first mentioned abutment shoulder.

6. In a collapsible filing drawer or the like a 15 wall of paper board or similar non-metallic material having an edge thereof embraced by a metallic binder, such binder consisting of a strip of metal conformed to be generally U-shaped in cross section, one of the sides of the binder 20 being provided at its free edge with a wall indenting lip, the other side of the binder being provided at an intermediate portion with a pair of spaced apart longitudinally extending wall indenting beads which project toward the first 25 mentioned side of the binder, said beads lying on opposite sides of a plane, transverse of the wall, which includes said indenting lip, and the free edge of said binder beyond said beads extending outwardly from said wall and shaped to provide 30 a hook flange.

7. In a collapsible filing drawer or the like a wall of paper board or similar non-metallic material having an edge thereof embraced by a metallic binder, such binder consisting of a strip of 35 metal conformed to be generally U-shaped in cross section, one of the sides of the binder being provided with a pair of spaced apart longitudinally extending wall indenting beads which project toward the other side of the binder, the metal 40 which lies between such beads being of concavo-convex cross section and presenting its concave face to the other binder side, the major portion of the convex face of said concavo-convex section lying below the surface of the adjacent portion of said binder, such other binder side being provided at its free edge with a wall indenting lip adapted to cause a deflection of wall material 45 against and into said concave face when the edge portion of the wall is embraced by the binder 50 and squeezed between the sides of the latter.

8. A blank for use in fabricating a collapsible drawer or the like comprising a paper board member scored to provide a bottom portion and side walls and end walls secured thereto along 55 the score lines, generally U-shaped metallic binders extending around and enclosing substantially the entire perimeter of the blank to provide smooth reinforced vertical and horizontal edges for each of the side and end walls when these 60 walls are folded upwardly to form a drawer, each U-shaped member having at its free inside edge an offset lip running from end to end and extending toward the center of the wall upon which it is mounted, said offset lips adapted to cooperate 65 with a locking strip to hold said drawer in erected position, and a portion of said offset lips being removed from the ends of the portion of the U-shaped member embracing the horizontal edges of the walls.

HARRY L. FELLOWES.
